UNITED STATES PATENT OFFICE.

FRANK E. SHAILOR, OF DETROIT, MICHIGAN, ASSIGNEE TO FRANK KUHN, OF DETROIT,
MICHIGAN.

ELECTRICAL HEATING UNIT.

1,191,238.

Specification of Letters Patent. Patented July 18, 1916.

Application filed October 25, 1913. Serial No. 797,186.

To all whom it may concern:

Be it known that I, FRANK E. SHAILOR, a citizen of the United States of America, residing at Detroit, in the county of Wayne 5 and State of Michigan, have invented certain new and useful Improvements in Electrical Heating Units, of which the following is a specification, reference being had therein to the accompanying drawings.

10 The invention relates to electrical heating units of that type in which the resistor is insulated and armored.

More specifically, the invention relates to that class in which the resistor is distributed 15 in a plane, with the armor arranged in a parallel plane.

It is the object of the invention to facilitate the conduction of the heat from the resistor into the armor. Further to increase 20 the radiation from the armor, and further to otherwise improve the construction as hereinafter set forth.

In the drawings: Figure 1 is a perspective view of an electrical heating unit constructed in accordance with my invention; 25 and Fig. 2 is a cross section.

It is usual in the construction of heating units of the type above described to insulate the resistor by sheets of flat insulating 30 material, such as mica, over which is laid a flat armor plate clamped to the resistor at the margin and at intermediate points.

It is an object to obtain the best heat conduction between the resistor and the armor, 35 by holding all portions of the inner surface of the latter in firm contact with the insulation which separates it from the resistor. In practice, however, such an effect is not obtained for the reason that the surface of the armor is never exactly parallel to the surface of the insulation and only contacts with the latter at points distributed over its area. Furthermore, the differential 40 expansion of the insulating material and the metal will cause more or less buckling and increase the separation therebetween. In addition to lack of contact the dissipation 45 of heat from the armor is limited by the extent of its exposed surface which, being a plane, is the minimum within fixed 50 dimensions.

With my improved construction better heat conduction and increased radiation is obtained by substituting for the plane armor.

a roughened surface. This, while theoretically decreasing the surface contact with the insulation, practically increases such contact by providing a larger number of points of bearing. The roughened surface is also of greater area than a plane surface 55 so that the radiation is increased, while a more pleasing appearance is produced, especially after the surface of the armor becomes corroded than with the plane armor.

In specific construction, A is a flat unit 60 of any desired shape or dimensions and provided with the usual terminal contacts B and B'.

C is the resistor.

D and D' are insulating sheets covering 70 the opposite faces of the resistor, and E and E' the armor plates. These armor plates are formed of roughened metal, preferably by forming indentations in its surface as indicated in Fig. 2. The plates E and E' 75 are clamped in position by suitable means such as turning over a marginal flange F and by intermediate tie connections G. Thus the various points in the surface will be clamped against and to a limited extent 80 embedded in the insulation to produce good heat conduction, while the increased area of the outer surface will correspondingly increase the radiation.

What I claim as my invention is:

1. An electrical heating unit comprising 85 a resistor having an extended flat surface, flat insulating sheets disposed on opposite sides of said resistor, and an armor plate consisting of relatively thin corrugated 90 metal sheets clamped to the exposed sides of the insulating sheets.

2. In an electrical heating unit consisting 95 of a resistor, flat insulating sheets disposed on opposite sides of said resistor, and an armor plate consisting of corrugated sheets clamped to the opposite sides of the insulated sheets, the contacting parts of said corrugated sheet against the insulating 100 sheets being embedded in said insulating sheets thereby increasing the heat conduction of the heater.

In testimony whereof I affix my signature in presence of two witnesses.

FRANK E. SHAILOR.
